Owen, Owen & Campion.

UNITED STATES PATENT OFFICE.

WILLIAM G. BERGMAN, OF POINT PLACE, OHIO.

RECUPERATOR.

Application filed January 9, 1922. Serial No. 527,874.

To all whom it may concern:

Be it known that I, WILLIAM G. BERGMAN, a citizen of the United States, and a resident of Point Place, in the county of Lucas and 5 State of Ohio, have made an Invention Appertaining to a Recuperator; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention has for its object to provide a recuperator for furnaces that are heated by a gas, such as producer gas mixed with air, that is directed into the furnace by a suitable burner, and wherein the recuperator 20 is built in cylindrical turret form, having a mixing nozzle and chambers for the producer gas, air and for receiving the burnt gases from the furnace, and wherein the air and the producer gas are heated by the 25 heat of the burnt gases.

The invention may be contained in structures that may be varied in their details by those skilled in the art. To illustrate a practical application of the invention I 30 have selected a structure containing the invention as an example of such structures, and shall describe it hereinafter. The structure selected for purposes of illustration is shown in the accompanying drawings.

35 Figure 1 of the drawings is a sectional, partly broken view of the recuperator selected as an example of recuperators containing my invention. Fig. 2 is a sectional view taken on the line 2—2 indicated in Fig. 1. Fig. 3 is a sectional view taken on the line 3—3 indicated in Fig. 1. Fig. 4 is a sectional view taken on the line 4—4 indicated in Fig. 1.

1 indicates a suitable base for the recuperator structure which may be formed of concrete or any other suitable material. A pier 5 is located on the base 1 and is provided with a passageway 2 for conveying fuel gas and also with a clean-out chamber 50 3 that connects with the passageway 2. One end of the chamber 3 may be closed by a suitable refractory plate or plug 4. The chambers 2 and 3 may be cleaned of deposits from the fuel gas when the plug 4 is removed. The cylindrical pier 5 supports a platform or base 6 of refractory material

on which are built the cylindrical walls that form the chamber passageways of the recuperator.

The recuperator is formed of a pair of 60 cylindrical, substantially concentric vertical walls 7 and 8 that are formed of refractory material. The outer wall 7 is preferably formed of brick and is built so as to render the wall 7 heat insulating as much as possible, while the wall 8 is a heat conducting wall and is formed of large tiles having horizontal abutting surfaces. The wall 8 forms the inner chamber that communicates with the chamber 2 formed in the pier 5. 70

The wall 7 is a relatively thick heavy wall, while the wall 8 is a very thin wall, but sufficiently thick to withstand the compression strains and to maintain the load produced by the weight of the wall 8. The 75 space between the walls is connected to chambers 9 formed in the pier below the supporting platform 6 from which gases are drawn through the passageways 10 by a suitable exhaust means, such as a suction so fan, or if desired, a stack.

Within the annular shaped chamber formed between the walls 7 and 8 are located a plurality of tubular vertical passageways, each formed by a plurality of tiles 85 11 placed vertically one above the other and having horizontal abutting edges or surfaces. The vertical rows of tiles are disposed in spaced relation within the outer chamber formed between the walls 7 and 8 90 and in spaced relation with respect to the walls 7 and 8. If desired, suitable abutting shoulders may be formed on the ends of the tiles to receive the abutting edges of adjoining tiles, but preferably the tiles are 95 separated by the blocks 12 having abutting shoulders for receiving the ends of the tiles. The blocks 12 are located opposite the joints formed in the tiles 13 that form the wall 8, and projecting blocks 14 and 15 extend from 100 the inner and outer walls of the recuperator and contact with the blocks 12 located between the tiles 11. The blocks 14 are spaced around the inner wall and the blocks 15 are likewise spaced around the outer 105 wall, and vertical sides of the blocks abut between the tiles forming the inner wall and the tubular passageway and the outer wall, whereby the tiles forming the inner wall and the tiles that form the tubular passageways are secured from lateral displacement. 110

By this arrangement not only a large heat

area for the receipt or discharge of heat by or from the gases and air is provided, but also means for readily conducting the heat from the outer chamber to the inner chamber and passageways is formed. Also by reason of the cylindrical arrangement of the parts the radial expansion produced by the heat affects all parts of each wall of the chambers and the passageways alike and thus the joints between the parts of the walls are maintained in their sealed condition by the weight of the walls, which is not disturbed by unequal expansion of parts of the walls, and moreover the walls are maintained in their definite relation with respect to each other by the abutting laterally disposed contacting members located at the joints of the tiles.

The lower ends of the tubular passageways formed by the tiles 11 communicate with the chamber 16 formed in the pier 5 to which air may be directed, from a blower, through the passageways 20 which are disposed on opposite sides of pier 5 and so as to form with the chambers 16 two pairs of transversely located passageways, and arranged that when the ends of the passageways 20 are opened, the chamber 16 and the passageways 20 may be cleaned out. The air passes into the chamber 16 and up through the tubular passageways formed by the tiles 11. The upper end of the tubular passageways communicate with the chamber 17 formed in the burner 18. The burner 18 is supported on the top of the walls 7 and 8 and the chamber formed within the wall 8 communicates with the chamber 19 of the burner. The air passes around in the chamber 17, which, at the end of the nozzle 21, forms a mixing chamber 22. If desired, a nozzle 23 may also connect the chamber 17 with the chamber 19, the nozzle 23 being located in axial alignment with the nozzle 21 and so as to direct a central stream of the air from the chamber 17 into the stream of producer gas that rises through the inner chamber of the recuperator. If desired, a movable refractory block or plug 26 may be supported in the wall of the chamber 17 for closing the nozzle 23. The air and gas thus mixed pass from the mixing chamber 22 into the furnace 24 where they ignite and burn and are returned to the chamber 25 formed in the top of the recuperator. The hot burnt gases pass down between the walls 7 and 8 and between the bricks or blocks 14 and 15 and between the tubular passageways formed by the rows of tiles 11 and through the chamber 9 and out through the passageways 10. While the burnt gases are thus passing through the outer chamber of the recuperator the tiles are heated and the heat is conveyed through the tiles forming the inner chamber and the tubular passageways to heat the producer

gas, or further heat the producer gas if the producer gas first passes from checker work to the recuperator, and to heat the air passing through the tubular passageways, and thus raise the temperature of the mixture formed in the mixing chamber 22 to near its kindling point.

I claim:

1. In a recuperator having a pair of circular, substantially concentrically arranged walls forming an inner passageway for producer gas and an outer annularly arranged passageway for burnt gases, a plurality of tubular passageways for air located in the outer passageway for burnt gases.

2. In a recuperator having a pair of circular, substantially concentrically arranged vertical walls forming an inner passageway for producer gas and an outer annularly arranged passageway for burnt gases, a plurality of vertical tubular passageways for air located in the outer passageway for burnt gases.

3. In a recuperator having a pair of circular, substantially concentrically arranged vertical walls forming an inner passageway for producer gas and an outer annularly arranged passageway for burnt gases, a plurality of vertical tubular passageways located radially equidistant from the axis of the walls for air and located in the outer passageway for burnt gases.

4. In a recuperator having a pair of circular substantially concentric vertical walls forming an inner passageway for producer gas and an outer passageway for burnt gases, the inner wall formed of tubular refractory tile having horizontal abutting edges, a plurality of vertical tubular passageways for air located radially equidistant from the axis of the central passageway and formed of a plurality of tile having horizontal contacting edges and located in the passageways for burnt gases.

5. In a recuperator having a pair of circular substantially concentric vertical walls forming an inner passageway for producer gas and an outer passageway for burnt gases, the inner wall formed of tubular refractory tile having horizontal abutting edges, a plurality of vertical tubular passageways for air located radially equidistant from the axis of the central passageway and formed of a plurality of tile having horizontal contacting edges and located in the passageways for burnt gases, and radially extending relatively spaced refractory members supported in the inner and outer walls for laterally securing the tubular members.

6. In a recuperator having a pair of circular, substantially concentrically arranged walls forming an inner passageway for producer gas and an outer annularly arranged passageway for burnt gases, a plurality of tubular passageways for air located in the

outer passageway for burnt gases, a burner having chambers connected to the chambers and passageways of the recuperator.

7. In a recuperator having a pair of circular, substantially concentrically arranged walls forming an inner passageway for producer gas and an outer annularly arranged passageway for burnt gases, a plurality of tubular passageways for air located in the outer passageway for burnt gases, a burner located above the recuperator and having chambers and passageways registering with the chambers and passageways of the recuperator.
- 10 8. In a recuperator having a pair of circular, substantially concentrically arranged walls forming an inner passageway and an outer annularly arranged passageways, a plurality of tubular members forming tubular passageways located in the outer passageway, the passageways forming conduits for air and producer and burnt gases for heating the

air conducted through one of the passageways.

9. A recuperator and a fire pot or furnace 25 coacting therewith, the recuperator having a combustion chamber discharging into the fire pot or furnace, a gas passage discharging into the combustion chamber, a plurality of spaced air flues extending contiguous to the 30 gas passage and discharging into the combustion chamber, and means for directing the heated products of combustion from the pot or furnace against a wall of said combustion chamber and then causing the flow of said 35 combustion products through the spaces between the air flues and gas passage to a point of final discharge and in a direction reverse to the direction of flow of the air and gas.

40 In testimony whereof, I have hereunto signed my name to this specification.

WILLIAM G. BERGMAN.
